UNITED STATES PATENT OFFICE.

CHARLES AMES ALDEN, OF STEELTON, PENNSYLVANIA.

RAILWAY-SWITCH APPARATUS.

1,341,161.

Specification of Letters Patent. Patented May 25, 1920.

Application filed October 1, 1919. Serial No. 327,626.

To all whom it may concern:

Be it known that I, CHARLES AMES ALDEN, a citizen of the United States, and residing at Steelton, Dauphin county, State of Pennsylvania, have invented certain new and useful Improvements in Railway-Switch Apparatus, of which the following is a specification.

The present invention relates to railway switch apparatus and more particularly to means for operating the signal in connection therewith.

The usual signal device used in connection with railway switches is so disposed and actuated that the angular movement of the signal is substantially proportional to the lateral movement of the switch. Hence the switch point may be moved either maliciously or because of breakage of the connections a small distance from the fixed rail, without giving a perceptible movement to the signal which usually consists of a target or lamp. This small opening may cause a derailment of a train moving toward the switch, although the signal indicates safety.

The principal object of the present invention is to provide a signal and means for operating the same so that the angular motion thereof is accelerated during the first and last portions of the throw of the switch so that the signal will indicate danger unless the switch is in a safe position.

Other objects and features of novelty will be apparent from the description taken in connection with the drawings, in which—

Figure 1 is a top plan view of a switch stand and a portion of a switch embodying the present invention;

Fig. 2 is a top plan view of the signal operating mechanism, certain parts being broken away, showing the position of the parts after the switch has been moved a fraction of its throw;

Fig. 3 is a sectional elevation taken substantially on the line 3—3 of Fig. 2;

Fig. 4 is a perspective view of the escape-
ment cam;

Fig. 5 is a perspective view of the operating cam;

Fig. 6 is a perspective view of the operating crank or lever;

Fig. 7 is a sectional elevation through the hub of the operating lever; and

Fig. 8 is a perspective view of the mast supporting member.

Referring to the drawings, the reference

numeral 10 indicates a switch stand of any desired type having a rod 11 adapted to be connected to the switch to throw the same.

In the present embodiment of the invention the signal and means for operating the same are assembled with the switch stand, although it will be obvious that the signal and its actuating mechanism might be disposed in other locations. As shown, the base plate 12 of the switch stand, which is secured to the ties 13 has two parallel spaced bolts 14 and 15 projecting upward therefrom. The outer of these bolts has the hub 16 of an actuating lever or crank rotatably mounted thereon, the bore having a bushing 17. As clearly shown in the drawings this lever has an arm 18 provided with an operating pin 19 adjacent the free end thereof. Further the hub 16 has a lug 20 into which is threaded a rod 21. The free end of this rod is adapted to be connected so that movement of the switch will turn the lever. As shown this is accomplished by an adjustable rod 22 at one end secured to the switch point 23 and at the other end to the rod 21. It will be seen that the angular movement of the operating lever may be varied by adjusting the rod 21 in the lug 20.

The signal is mounted on a mast which comprises a shaft 24 rotatably mounted in a bar 25 the ends of which are held in place by the bolts 14 and 15. A signal supporting member 26 is secured to the upper end of the shaft 24, said member being formed with a socket to receive said shaft, and the two parts being connected for rotation together in any suitable manner as by means of the pin 27. Downward movement of the shaft and associated parts is prevented by the lower end of member 26 resting on the boss 28 of the bar 25. The shaft 24 projects below the bar 25 and has an operating cam 29 fastened thereto for rotation therewith as by means of the pin 30. As clearly shown in Fig. 5 this cam is provided with a cam groove consisting of the curved portion 31, which is concentric with the axis of bolt 14 when the cam is in central position. At the ends of the curved portion 31, the cam groove has the offset portions 32 and 33 extending in a generally radial direction with respect to the axis of the cam. The cam is also provided with the escape-
ment stops 34 and 35, the function of which will appear hereinafter.

When the switch points are at one end

of their throw, the parts are in the positions illustrated in Fig. 1. Now if for any reason the switch point is moved a slight distance away from the rail, the motion thereof will be communicated to the operating lever and the pin 19 thereof disposed in the offset portion 32 of the cam groove, will act on the cam member to swing it about the axis of the mast, thereby turning the mast and the signal. The arrangement of the parts is such that this slight motion of the switch points will turn the mast and signal through a considerable angle. Thus the signal will be turned sufficiently so that the engineer will be warned that the switch is not safe. In Fig. 2 of the drawings the positions of the parts are illustrated after the switch point has moved only about 20% of its throw from the position illustrated in Fig. 1. This slight motion of the switch point however has been sufficient to turn the signal mast through an angle of substantially 45 degrees. In throwing the switch therefore the first portion of the motion thereof carries the pin 19 out of the portion 32 of the cam groove into the concentric portion 31, the cam and mast having been turned through substantially 45 degrees in this time. Further motion of the switch moves the pin 19 in the concentric portion of the cam groove and therefore transmits no motion to the cam. However when the pin 19 comes opposite the offset portion 33 of the cam groove, the cam member will be turned and the pin will travel outward to the outer extremity of this offset portion 33, the cam member and mast being turned through substantially 45 degrees while the pin is moving in this offset 33. When the switch is turned in the opposite direction, the pin will travel in the cam groove in the reverse direction thereby turning the mast through 45 degrees during the first portion of the switch movement, transmitting no motion to the mast during the intermediate portion of the switch movement and finally turning the mast through the remaining 45 degrees of its 90 degree movement only at the end of the throw.

It is desirable to hold the signal mast against movement when the pin 19 is in the concentric portion of the cam groove, that is when the motion of the switch is not being communicated to the signal mast. For this purpose an escapement cam 36 illustrated in Fig. 4 is provided. As clearly shown in the figures, this escapement cam is pivotally mounted on the bolt 15 between the bar 25 and a projection 37 on the housing of the switch stand 10. This escapement cam is provided with a concaved edge surface 38 adapted to coöperate with the pin 19 as will presently be explained. On its under side it is formed with the oppo-

sitely disposed curved surfaces 39 and 40, the surface 40 adapted to coöperate with the escapement stop 34, and the surface 39 with the escapement stop 35. When the crank pin 19 travels from the position illustrated in Fig. 1 to the position illustrated in Fig. 2, it moves along the curved surface 38 but without in any way moving the escapement cam. The operating cam however is swung on its pivot as previously explained, and the escapement stop 34 is brought into engagement with the surface 40 on the escapement cam, this stop engaging said surface at about the time the pin 19 enters the concentric portion of the cam groove. Referring to Fig. 2, it will be seen if the operating cam with the signal should be forced to turn in a clockwise direction, the stop 34 would abut the surface 40, but swinging of the escapement cam 85 above its axis would be prevented by the curved surface 38 striking the pin 19. However when the pin 19 reaches an intermediate portion of the concentric portion 31 of the cam groove, it strikes the opposite portion of the surface 38 of the escapement cam and turns it on its pivot, carrying the escapement cam to a position so that it will prevent displacement of the signal when the switch is operated in the opposite direction.

Although a specific embodiment of the invention has been described in detail, it is to be understood that the invention is not thus limited, but includes modifications and changes which come within the scope of the appended claims.

Having thus described the invention, what is claimed as new and desired to be secured by Letters Patent is:

1. The combination with a switch, a member movable with said switch, a signal mast, and means operably connecting said member and mast to turn the latter unequal amounts for equal movements of said member, the movement of the mast being greatest at the ends of the throw of the switch.
2. The combination with a switch, a member movable with said switch, a signal mast, and means operably connecting said member and mast to turn the latter through substantially half of its angle of movement while the switch is moved a small portion only at one end of its throw, and through substantially the other half of its movement while the switch is moved through a small portion only at the other end of its throw, the movement of the switch between said end portions having substantially no effect on the mast.
3. The combination with a switch, a member movable with said switch, a signal mast, and means operably connecting said member and mast to turn the latter unequal movements for equal movements of said member.

member including a cam associated with said mast.

4. The combination with a switch, a member movable with said switch, a signal mast, and means operably connecting said member and mast to turn the latter unequal amounts for equal movements of said member including a cam associated with said mast and means on the member engaging 10 and operating the cam.

5. The combination with a switch, a lever, means to turn said lever in proportion to the movement of the switch, a signal mast, a cam associated with said mast, means on the lever engaging said cam, the cam being formed to give unequal angular movements to the mast for equal angular movements of the lever.

6. The combination with a switch, a member movable with said switch, a signal member, a cam associated with one of said members, means connected with the other member engaging said cam, the cam being formed to effect unequal movements of the 25 signal member for equal movements of the switch.

7. The combination with a switch, a member movable with said switch, a signal mast, means connecting said member and mast 30 constructed and arranged to move the mast only at the end portions of the throw of the switch, and means holding the mast against movement during the intermediate portion of the switch throw.

8. The combination with a switch, a member movable with said switch, a signal member, a cam associated with one of said members, means connected with the other member engaging said cam, the cam being formed 40 to effect movement of the signal member only at the end portions of the throw of the switch, and means holding the signal against movement during the intermediate portion of the switch throw.

9. The combination with a switch throwing mechanism including a support, a rotatable signal, a member adapted to be movably connected with the switch, said parts carried by the support, means connecting the member and signal to turn the latter only at the end portions of the switch

throw, and means holding the signal against movement during the intermediate portion of the switch throw.

10. The combination with a switch throwing mechanism including a support, a rotatable signal, a lever having an arm adapted to be connected to move with the switch, a cam member associated with the signal, the other arm of the lever engaging 55 said cam, the parts being constructed and arranged to move the signal only at the end portions of the switch throw, and means holding the cam against movement during the intermediate portion of the switch 60 throw.

11. The combination with a switch stand having switch throwing mechanism, a rotatable signal on said stand, a two armed lever pivoted on the stand, one arm being 70 adjustable in length and adapted to be connected to be moved with the switch, a pin on the other arm, and a member having a cam groove associated with the signal, said pin being disposed in said groove, for 75 the purpose set forth.

12. The combination with a rotatably mounted signal, of means to actuate said signal including a member associated with the signal and a member adapted to be 80 actuated by a switch, one of said members having a cam surface and the other means coöperating with said surface, the cam surface being formed to transmit movement from the switch actuated member to the 85 signal member only at the ends of the throw of said switch actuated member.

13. The combination with a rotatably mounted signal mast, of a member having a cam groove connected to said mast, a 90 lever having one arm adapted to be actuated by movement of a switch and a second arm having a pin disposed in said groove, the cam groove being formed to effect movement of the mast only at the end 95 portions of the switch throw, and an escapement cam coöperating with said pin to restrain movement of the mast during the intermediate portion of the switch throw.

In testimony whereof I affix my signature. 100

CHARLES AMES ALDEN.
